UNITED STATES PATENT OFFICE.

DAVID BLOCH AND PETER E. MALMSTROM, OF NEW YORK, N. Y.

WINDOW-SHADE FIXTURE AND ROLLER.

SPECIFICATION forming part of Letters Patent No. 294,358, dated March 4, 1884.

Application filed December 10, 1883. (No model.)

To all whom it may concern:

Be it known that we, DAVID BLOCH and PETER E. MALMSTROM, citizens of the United States of America, residing at New York, in 5 the county of New York and State of New York, have invented certain new and useful Improvements in Window-Shade Fixtures and Rollers; and we do hereby declare the following to be a full, clear, and exact description of 10 the invention, such as will enable others skilled in the art to which it appertains to make and use the same.

This invention relates to that class of shade-fixtures that are provided with springs, by 15 means of which the shade is automatically wound upon the roller. The manner heretofore employed to accomplish this was to insert in one end of a roller especially prepared for the purpose a spiral spring which was 20 wound around a spindle when the shade was pulled down. When the shade was let up, the spring, unwinding, would, by its force, wind the shade around the roller. While it is not denied that this mechanism was to a certain extent operative, yet it possessed disadvantages 25 that it is the object of our invention to overcome. It was necessary with the roller or fixtures heretofore employed to use a stick or roller expressly made for the purpose, while 30 with the use of our invention we can employ the ordinary roller so extensively in use. It is obvious that the cost of our fixtures is but a small percentage of that of others, while it possesses the advantage of being fixable in 35 many positions. One other great advantage that our invention possesses over others is that it is not necessary to first wind the spring, since it is only necessary to roll up the shade and set the same, and the spring is wound up by 40 pulling the shade down. The spring, being an ordinary clock-spring, cannot possibly get out of order. In the use of Hartshorn's rollers, if by accident, while tacking the shade on the stick, a tack is driven the least too deep, the 45 operation of the spring is stopped and it becomes useless. It is immaterial in what position the shade may be when removed from the fixture.

In the accompanying sheet of drawings, Figure 1 represents an inside view of a window with shade-fixture affixed; Fig. 2, a view of the casing with the top removed, showing the mech-

anism; Fig. 3, a cross-section on the line *x x*; Fig. 4, an end view of the roller, showing the engagement of the pinion of the disk *E* with 55 the pinion-retaining bracket *D*. Fig. 5 is a front view of Fig. 4. Fig. 6 is a perspective view of the roller and fixtures when in position to be operated.

Similar letters indicate corresponding parts. 60

A represents the casing having the angles *n*, provided for the purpose of either attaching the fixture at the end or side. The roller *B* is provided at its opposite ends with the metallic cap-pieces *E* and *K*. From *E* extends the 65 cylindrical stud *P*, which is loosely journaled in the bracket *D*. The cap-piece *K* is provided with a similar prolongation, hollowed out, as shown, to correspond with the flattened sides of the truncated prismoidal end *l* 70 of the shaft *e*, journaled within the casing *A*. The shaft *e* is provided with a longitudinal groove for engagement of the angled pawl *f*, turning on the supporting-pin *d*. A pinion, *c*, upon the shaft *e* engages with the teeth of 75 a wheel, *a*, fixed upon the loosely-journaled shaft *b*. A band-spring, *g*, adjacent to the face of the wheel, is attached at its inner end to the shaft *b*, and at its outer end to the fixed pin *h*. 80

The parts being arranged and disposed as described, the operation of the device is as follows: The curtain being first wound upon the roller *B*, the spring *g* being in an uncoiled condition, the curtain may be lowered to any 85 desired height by drawing it down in the ordinary manner. The lowering of the curtain causes the roller *B* to revolve in its bearings. The revolution of the roller insures a like movement of the shaft *e*, to which it is clutched 90 by means of the prolongation *l*. The pawl *f* glides over the surface of the shaft. The fixed pinion *c* upon the shaft *e* causes the revolution of the engaging toothed wheel *a* in an opposite direction, and the spring *g* accordingly 95 begins to wind upon the shaft *b*.

To arrest the curtain at approximately any desired point it is merely necessary to hold it at that point for a moment, and then allow its slight retrograde movement until the pawl *f* 100 falls into the groove in the shaft *e*. To release the curtain from that position and rewind it partially or completely, the pawl, by a quick downward movement of the curtain, is

thrown out of the groove in the shaft *e*, whereupon the resiliency of the spring *g*, communicated through the wheel *a*, pinion *c*, and shaft *e*, causes a revolution of the roller *B* in the contrary direction and rewinds the curtain. Its upward movement may in a similar manner to that before described be stopped at any desired height.

The casing *A* is made in two sections, cast separately, the inner plate being fitted to the main body, as shown in Fig. 6.

Having described our invention, what we claim is—

1. In an automatic spring curtain-roller, the arbor *b*, provided with the spring *g* and toothed wheel *a*, in combination with the shaft *e*, longitudinally grooved and formed with the truncated prismoidal end, the pinion *c*, carried by

said shaft and pawl, and the roller *B*, provided with the cap-piece *K*, for clutching the end of shaft *e*, substantially as shown and described.

2. In an automatic spring curtain-roller, the roller *B*, provided with the cap-piece *K*, in combination with the grooved shaft *e*, and pawl for engaging in said groove, the cap-piece and shaft being provided, respectively, with interlocking elongations, as shown and described.

In testimony whereof we affix our signatures in presence of two witnesses.

DAVID BLOCH.
P. E. MALMSTROM.
